United States Patent Office

Des. 200,938
Patented Apr. 20, 1965

200,938

AIR DIFFUSER

Warren R. Hedrick, Holland, Mich., assignor to Hart & Cooley Manufacturing Co., Holland, Mich., a corporation of Delaware

Filed Jan. 16, 1964, Ser. No. 78,232

Term of patent 14 years

(Cl. D62—4)

FIG. 1

FIG. 2

FIG. 3

FIG. 4

FIG. 5

FIG. 6

FIG. 1 is a top plan view of an air diffuser showing my new design;

FIG. 2 is a front elevational view of the air diffuser shown in FIG. 1;

FIG. 3 is an end elevational view looking toward the left-hand end of FIG. 2;

FIG. 4 is an end elevational view looking toward the right-hand end of FIG. 2;

FIG. 5 is a transverse sectional view thereof taken along the plane of line 5—5 of FIG. 2; and,

FIG. 6 is an enlarged fragmentary view of the circular element at the right-hand end of the diffuser in FIG. 2.

The rear face is flat and plain.

I claim:

The ornamental design for an air diffuser, substantially as shown and described.
